UNITED STATES PATENT OFFICE.

WILLIAM H. POWELL, OF PITTSBURG, PENNSYLVANIA, ASSIGNOR OF ONE-HALF TO JOHN MURTHA, OF PITTSBURG, PENNSYLVANIA.

STEAM-TRAP.

SPECIFICATION forming part of Letters Patent No. 729,509, dated May 26, 1903.

Application filed February 15, 1902. Serial No. 94,162. (No model.)

To all whom it may concern:

Be it known that I, WILLIAM H. POWELL, a citizen of the United States, residing at Pittsburg, in the county of Allegheny and State of Pennsylvania, have invented a new and useful Improvement in Steam or Water Traps, of which improvement the following is a specification.

This invention relates to certain new and useful improvements in steam or water traps, and has for its object the provision of novel means whereby the valve will be automatically opened and closed under certain conditions.

The invention has for its further object to construct an apparatus of this character that will be extremely simple in its construction, strong, durable, and comparatively inexpensive to manufacture; furthermore, one that will be highly efficient in its operation.

With the above and other objects in view the invention consists in the novel construction, combination, and arrangement of parts to be hereinafter more fully described, and specifically pointed out in the claims.

In describing the invention in detail reference is had to the accompanying drawing, forming a part of this specification, and wherein like numerals of reference indicate like parts upon said drawing, which shows a vertical sectional view of my improved steam or water trap.

In the drawing the reference-numeral 1 indicates the water or steam inlet pipe, and 2 represents the inlet-pipe connecting to the elbow 3, communicating with the pipe 4, said pipe being secured in the casing 5. This casing 5 carries an upwardly-extending port 6, to the upper end of which is arranged a valve 7. This casing 6 also has an outlet-port 8 and communicating with the outlet-port 9 of a slidable casing 10. This slidable casing 10 is secured to a spherical chamber 11, which is pressed by means of a spring 12. The spring 12 has its upper end in engagement with the boss 14, which is held in position by the set-screw 15, extending through the boss 16 of the annular frame 17. The frame 17 is provided at its lower end with an integral collar 18, which is removably secured to the casing 5.

19 indicates a valve-seat arranged in the sliding casing.

In operation the steam is forced or injected through the inlet-pipe 1, following the direction of the arrows upwardly through the port 6 into the spherical chamber 11. The pressure of the steam within the said chamber will overcome the weight of the chamber and the pressure of the spring 12, and thus close the outlet-valve until the weight of the condensed steam in the chamber 11 is sufficient to open the valve, whereupon the said chamber 11 will be emptied.

The many advantages obtained by the use of my improved device will be readily apparent from the foregoing description, taken in connection with the accompanying drawing, and it will be noted that various changes may be made in the details of construction without departing from the general spirit of my invention.

Having fully described my invention, what I claim as new, and desire to secure by Letters Patent, is—

1. In a device of the character described, the combination of a casing having inlet and outlet ports formed therein, an annular frame provided at its lower end with an integral collar, said collar encircling the upper portion of the said casing and being secured thereto, a vertically-arranged pipe secured to the upper wall of the inlet-port, a valve secured to the upper end of the said pipe, a receptacle, and a valve-seat secured to the lower end of the said receptacle and having its lower end arranged in the upper end of the said casing, substantially as described.

2. In a device of the character described, the combination of a casing formed with inlet and outlet ports, a vertically-arranged pipe communicating with the inlet-port, a valve detachably secured on the upper end of the said pipe, a receptacle, a valve-seat detachably secured on the lower end of the said receptacle, an annular frame secured to the said casing, and a spring interposed between the said frame and receptacle.

In testimony whereof I have hereunto signed my name in the presence of two subscribing witnesses.

WILLIAM H. POWELL.

In presence of—

JOHN GROETZINGER,
M. HUNTER.
